SEMAUTOMATIC RESERVE CONTAINER
FOR LIQUID TANKS

George W. Johnson, Camden, N. J.

Application June 7, 1933, Serial No. 674,705

2 Claims. (Cl. 137—68)

My invention relates to new and useful improvements in a semi-automatic reserve container for liquid tanks and has for one of its objects to provide a relatively small reserve container having a spring actuated valve to normally close an opening in the bottom thereof.

Another object of the invention is to provide means for holding the valve in an open position after being manually opened.

Another object of this invention is to provide float mechanism for automatically actuating the holding means when the reserve container is filled with liquid to release the valve.

A further object of the invention is to provide a reserve container provided with an opening in the bottom thereof for liquid to flow into the container, a valve to normally close said opening, said valve being moved to the closed position by a spring and moved into the open position manually, a spring actuated catch to hold the valve in its open position, and float mechanism operated by the level of the liquid in the reserve container to release the catch and permit the valve to close when said reserve container is filled, said container remaining filled until such time as the contents are needed and the valve is opened manually.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this application, in which:—

Fig. 1 is a view of a part of a liquid storage tank partly broken away showing the reserve container therein which has a portion broken out to illustrate the valve mechanism above referred to and a visible indicator.

Fig. 2 is an enlarged fragmentary plan view of the container with portions of the top wall broken away.

Fig. 3 is a fragmentary view of the parts illustrated in Fig. 2, looking at them the same as shown in Fig. 1, but with the valve open.

Fig. 4 is a sectional view on the line 4—4 of Fig. 2.

In carrying out my invention as herein embodied, 5 represents a liquid tank of any desirable shape and size and one that is particularly adapted as a storage tank for gasoline in automobiles.

This tank has an outlet (not shown) and also an inlet 6 which may be normally closed by a cap 7 provided with a vent.

Said tank 5 comprises the usual walls, one of which is to be attached as the finishing operation of the complete tank. This attachable wall, for purposes of illustration, is designated herein as an attachable end wall 8, shown as welded in place although it may be otherwise secured. A bracket 9 of suitable or proper length has one end fixed to the attachable wall 8 and the opposite end to the exterior of a wall of the reserve container 10.

In the bottom of the reserve container is formed an opening 11 which functions both as an inlet 15 and an outlet and in the top of the container is formed a hole 12 concentric with the opening 11.

Where the tank 5 has a flat bottom, the reserve container is provided with buttons or feet 13 to space the bottom of the reserve container from the bottom of the tank, but where the latter is of some other shape so that the container can rest on the side walls, for instance, and thereby space the bottom of the container from the adjacent wall of the tank, the buttons, feet or lifts are unnecessary. It is essential that the bottom of the container be spaced from the tank to permit a free flow of the liquid in or out of the said container.

The opening 11 is controlled by a valve 14 urged toward its closed position by a spring 15 which engages said valve, as the movable element, and a guide bracket 16, as the stationary element. This valve has a valve stem 17 which projects through the guide bracket 16 and the hole 12 in the top of reserve container to a position adjacent the top of the tank 5 in the locality of the tank inlet 6 whereby said stem may be reached through the inlet 6 to actuate the valve manually against the action of the spring 15. In order to enable a person to open the valve 40 easily, the upper end of the stem may be fashioned into a loop or eye 18, or other equivalent formation, such as a hook.

On the valve stem 17 intermediate its ends and within the reserve container, preferably near the top of said container, is a tapered or frustoconical collar or latch keeper 19, with its smaller end uppermost. Under certain conditions, the nose of a catch 20 will engage under the larger end of the keeper to temporarily hold the valve 14 in an open position.

The catch 20 is suitably pivoted as to hangers 21 depending from the top of the container and a spring 22 engaging the tail of the catch urges the nose thereof toward the valve stem and the 55

keeper 19 carried thereby. On the tail of the catch is a projection or pin 23 which is in the path of upward travel of the float stem 24 carrying a float 25 on the free end pivoted at 26 to a suitable support or bracket 27, which may be fastened to a side wall of the reserve container, and the pivot means for the catch 20 may also be connected to this support, if desired.

While the hole 12 will vent the reserve container, a hole 28, for this purpose only, can be provided at the top of said container.

Before filling the tank 5, assuming the reserve container is empty, the valve 14 is opened. As liquid enters the tank it will run through the opening 11 into the reserve container and cause the float to rise. When the float reaches its uppermost position, the stem 24 thereof will engage the pin 23 on the catch and release the same from the keeper 19 permitting spring 15 to close the valve 14. This will retain the liquid in the reserve container.

Should all of the liquid in the storage tank be withdrawn at any time and it is temporarily impossible to replenish the same, the valve 14 may be withdrawn from its seat by lifting the stem 17 which will then permit the liquid in the reserve container to flow therefrom through the opening 11 into the tank. By elevating the parts to a sufficient height, the catch 20 will engage beneath the keeper and hold the valve open, while the liquid is draining from the reserve container and until said container is refilled during a subsequent filling of the storage tank.

In order that a person may readily ascertain whether or not the reserve tank is full or empty, I may provide said reserve container with a visible indicator or signal in combination with the above described mechanism for controlling the filling and emptying of said reserve container.

Where the reserve container is to have an indicator, the top wall of said container has a sight opening 28. To the underside of the top wall of the reserve container in the region of the sight opening 28 is pivoted a semaphore 29 as at 30 and said semaphore is provided with certain indication marks 31 and 32, such as "empty" and "full" respectively, which will be alternately visible through the sight opening 28 under certain conditions as will be presently more fully brought out.

Depending from the underside of the semaphore are a pair of spaced wings 33 and 34 between which operates a finger 35 carried by the float stem 24. Where the semaphore projects beyond the support 27, the latter has a notch 36 in its upper edge to permit said semaphore to freely swing back and forth.

Assuming that the reserve container is empty, the parts will be as shown in Figs. 2 and 3 and the indication mark 31 will be visible through the sight opening 28. As said reserve container is filled, the float will rise and the finger 35 will rotate in unison with the rotation of the float stem 24, causing said finger 35 to particularly engage the wing 34 and thus swing the semaphore about its pivot point until the other indication mark 32 moves into alignment with and becomes visible through said sight opening 28, thereby indicating to a person viewing the reserve container through the inlet 6 of the storage tank that said reserve container is full. At the same

time the valve mechanism will be operated as hereinbefore explained.

Whenever the valve 14 is opened and the contents of the reserve container drained therefrom, the float will descend and cause the finger 35 to particularly engage the wing 33 on the semaphore and thereby swing said semaphore to the position shown in Fig. 2, so that the indication mark 31 will be visible through the sight opening 28 whereby a person can readily ascertain that the said reserve container is empty. The indicator is a valuable adjunct to the rest of the apparatus, especially where the device is to be used by persons in nowise mechanically inclined, since it gives positive assurance to such persons that the container is empty or full.

Of course I do not wish to be limited to the exact details of construction herein shown and described as these may be varied within the limits of the appended claims without departing from the spirit of my invention.

Having thus fully described my invention, what I claim as new and useful is:—

1. A liquid container having an opening in its bottom to function as an inlet and outlet, a valve for closing said opening, a spring to move the valve into its closed position, a stem carried by said valve and projecting through the top of the container whereby said valve may be manually moved into an open position, a keeper on said valve stem within the container, a catch pivoted within the container for cooperation with the keeper to retain the valve in its open position, a spring to urge said catch into engagement with said keeper, a projection extending from one side of the tail of said catch, a float stem pivotally mounted within the container and so located that the projection on the catch is in the path of upward travel of said float stem, and a float on said float stem controlling the movements of said float stem according to the liquid level in the container, said float stem engaging the projection on the catch to trip the latter when the liquid level in the container reaches its highest position for releasing the keeper whereby the valve may be closed by its spring.

2. A liquid container having an opening in its bottom to function as an inlet and an outlet, a guide bracket mounted on the inner surface of a wall of said container and overlying said opening, a valve for closing said opening, a valve stem carried by said valve and slidably mounted in the guide bracket with the upper end of the stem projecting through a hole in the top of the container, a spring coiled about the stem and positioned between the valve and guide bracket to urge said valve toward its closed position, a conical keeper on the stem within the container adjacent the top of said container, hangers carried by the top of the container adjacent the position of the valve stem, a catch pivoted to said hangers and adapted to engage the base of the conical keeper to retain the valve in an open position, a spring to urge the nose of the catch into the path of travel of the keeper, a projection extending from one side of the tail of the catch, and float mechanism within the container to contact the projection and thereby disengage the catch from the keeper and permit the valve to close.

GEO. W. JOHNSON.
